UNITED STATES PATENT OFFICE.

MACK E. POLHEMUS, OF EATON RAPIDS, MICHIGAN.

FOLDING CRATE.

SPECIFICATION forming part of Letters Patent No. 651,168, dated June 5, 1900.

Application filed December 18, 1899. Serial No. 740,793. (No model.)

To all whom it may concern:

Be it known that I, MACK E. POLHEMUS, a citizen of the United States of America, residing at Eaton Rapids, in the county of Eaton 5 and State of Michigan, have invented certain new and useful Improvements in Folding Crates, of which the following is a specification, reference being had therein to the accompanying drawings.

10 This invention relates to crates, and particularly to that class which fold or collapse.

The object of the invention is to provide novel means for binding the bars in such manner as to allow a pivotal movement at their 15 intersection at the corners of the crate.

Furthermore, the object of the invention is to provide novel means for holding any one bar independently of the remaining bars, for if one of said bars becomes worn or broken 20 it may be removed and a new one substituted without disturbing the other bars.

Furthermore, the objects of the invention are to so form the bar-retainers that a protection is afforded to the end of said bars to prevent splitting or fracture and to so arrange 25 the bar-retainers as to minimize the friction and prevent wear on the bars as the sections are swung on their pivots.

Furthermore, the object of the invention is 30 to provide a novel means for applying the top and bottom to the crate and for rigidly retaining said top and bottom, as well as the sides and ends.

Finally, the object of the invention is to provide a crate which will possess advantages in 35 point of simplicity, durability, and efficiency and prove at the same time comparatively inexpensive.

With the above and other objects in view 40 the invention consists in the details of construction and in the arrangement and combination of parts, to be hereinafter more fully set forth and specifically claimed.

In describing the invention in detail reference will be had to the accompanying drawings, forming part of this specification, wherein 45 like characters denote corresponding parts in the several views, and in which—

Figure 1 is a side view of a crate embodying the invention. Fig. 2 is a plan view of

the same. Fig. 3 is a transverse section of the crate, and Fig. 4 is a view in perspective of the retainer.

In the drawings, 1 denotes a series of bars forming the sides of the crate, and 2 a series 55 for the ends. As in crates of usual construction, the side and end bars are alternately placed one above the other at their intersection near their ends, thus forming the corners. The inner faces of the bars are provided with grooves 3, approximately the depth of the diameter of the binding-wires 4, which are embedded therein. In the construction shown the binding-wire extends from the top to the bottom of the crate, through the strips 60 5, which are preferably heavier than the bars, in order to stand the wear incident to the use of the crate. The wires are clenched or otherwise secured in grooves formed in the surfaces of the strips. The strips and wires are 65 held in their relative positions by retainers 6, consisting, preferably, of square or rectangular plates each having a slot 7 extending from one edge to receive the binding-wires. When the bars are assembled, a plate is applied to 70 the edge of one of the bars with the binding-wires lying in the slot. The edges of the plate are then bent to lie against the sides of the bars, as fully shown, and when a plate is applied to the next succeeding bar in like 75 manner the plates will be in contact, and when the sections of the crate are swung on the binding-wires, which act as pivots, the wear is confined to the plates. Two plates are required at each end of a bar, one on each edge, 80 and when for any reason a bar is to be removed it is only necessary to bend up the outer edge of each of the plates embracing the edge of a bar, when it may be taken out and the same plates used on the substituted 85 bar.

The top 8 and bottom 9 are in all respects similar. Hence a detailed description of the construction and manner of securing the top will suffice as disclosing both the top and bottom. 95

End cleats 10 and 11 are provided, the former being of such length as to extend from the inner surface of one side to the inner surface of the other side of the crate, or, in other 100

words, it is of such length as to pass between the sides of the crate. The cleat 11 is of greater length than the width of the crate, and hence its ends protrude on each side, and 5 when the parts are assembled the ends rest on the upper edge of the top stay. The slats or bars of the top and bottom protrude beyond the cleats and are so positioned as to bear against the under surface of the strips 5 when 10 the cleat 11 is resting on the top bar of the sides and when the opposite end is suspended by the hooks 12, said hooks being swingingly secured to the cleat 10 in such manner as to permit the hooks to swing over and engage 15 the upper surfaces of the strips 5, in which grooves 13 are formed for their reception. The hooks may be retained in position against accidental displacement in any convenient manner.

20 The construction, operation, and advantages will, it is thought, be understood from the foregoing description, and it will be noted that changes in the proportions and other details of construction may be resorted to without departing from the scope of the invention.

25 Having fully described the invention, what I claim as new, and desire to secure by Letters Patent, is—

30 1. In a crate, a series of intersecting side and end bars having transverse grooves, binding-wires in the grooves and means for re-

taining the wires and bars in their proper relative positions.

2. In a crate, a series of intersecting end 35 and side bars, a wire engaging the surfaces of the bars at the corners, retaining-plates having slots to receive the wires; said plates being wider than the slats to which they are applied whereby they overlap the edges of the 40 bars and protect the same.

3. In a crate, a series of intersecting side and end slats having coinciding grooves at their point of meeting, a binding-wire in the grooves, retaining and antifriction plates between the meeting edges of the bars, said plates having slots to receive the wires and being of such width as to overlap the edges of the bars.

4. In a crate, a top and bottom comprising 50 cleats and bars projecting beyond the cleats, one cleat being longer than the width of the crate and the other cleat shorter than the width thereof, hooks pivoted to the shorter cleats and adapted to support one end while 55 the bars of the top or bottom bear against the strips and the protruding ends of the cleat engage the bars of the side.

In testimony whereof I affix my signature in the presence of two witnesses.

MACK E. POLHEMUS.
